INVENTOR
CHARLES W. EADS

by - ATTORNEY

Lincoln Johnson

UNITED STATES PATENT OFFICE.

CHARLES W. EADS, OF OAKLAND, CALIFORNIA.

FINGER-NAIL-CLEANING COMPOUND.

Application filed September 27, 1921. Serial No. 503,700.

To all whom it may concern:

Be it known that I, CHARLES W. EADS, a citizen of the United States, and a resident of the city of Oakland, county of Alameda,

6 State of California, have made a new and useful invention—to wit, Improvements in Finger-Nail-Cleaning Compounds; and I do hereby declare the following to be a full, clear, concise, and exact description of the 10 same.

This invention relates particularly to a cleansing and bleaching compound adapted to be used for removing accumulations on finger nails and bleaching the same.

15 A further object of this invention is to provide a cleansing and bleaching compound, shaped as a shaft, containing an abrasive substance, a bleach and a binder and of the consistency of a semi-solid.

20 A still further object is to provide a cleansing and bleaching compound shaped as a shaft and having a handle or casing means for holding or closing the same and which assembled article of manufacture will 25 be superior in point of simplicity of inexpensiveness or construction, positiveness of operation, facility and convenience in use and general efficiency, the use of which will not cause injury to the nails on a person's hands 30 or feet. The other objects and advantages will appear as the description progresses.

In this specification and the annexed drawings, the invention illustrated in the form considered to be the best, but it is to be understood that the invention is not limited to such form, because it may be embodied in other forms; and it is also to be understood that in and by the claims following the description, it is desired to cover the invention in whatsoever form it may be embodied.

In the accompanying one sheet of drawings:

Fig. 1 indicates a shaft of the compound 45 constructed in accordance with my invention.

Fig. 2 represents a side elevation partly in section of a casing for containing a shaft of my compound.

50 Fig. 3 represents a modified form of casing having the compound contained therein.

The nails on the fingers and toes of the human being, particularly the nails on the fingers, are more or less conspicuous. Dirt, 55 detritus and the like accumulates on top of, and more particularly, beneath the end of

the nail and for other than sanitary reasons, the appearance of a person's hands is effected by the neatness or untidiness of keeping the 60 nails.

Scientific treatment of the nails requires that the same be cleansed not by the blade of a sharp knife, but better with soft orange sticks and the like, which does not injure the 65 texture of the nail, but treats it so that a hard, firm surface results to which accumulations will not readily adhere.

My invention contemplates providing a 70 cleansing and bleaching compound shaped, as a shaft, having a diameter of approximately one sixteenth of an inch. The compound of the shaft will preferably be formed of an abrasive substance, a bleaching element and binding material, whereby the

same might be moulded or shaped in any 75 desirable length, diameters or shapes. In the forming of my compound, I have found that any number of binders such as paper pulp, clay, wax, tallow, soap or the like may be used, suitably mixed with predetermined 80 proportions of a bleaching element, such as any of the alkaline salts or acids or ammonia, peroxide of hydrogen, "listerine" and the like to which will be added an abrasive or cutting substance such for instance as 85 chalk, pumice or whiting. It is to be understood that suitable quantities of the named elements or any parts or combinations thereof would be mixed in a desired proportion and permitted to set or attain the 90 consistency of a semi-solid, (the nature of which would be akin to a colored crayon).

A shaft of the compound described, may be thus effectively used for removing accumulations from beneath the finger nails the 95 abrasive material in the said shaft tending to cut or remove the clinging dirt, but at the same time wearing away sufficiently to rub the bleaching element against the under side of the nail to whiten or bleach the same. 100

In order to facilitate the use of my compound it is desirable that the same be contained within a housing to eliminate the possibility of the shaft compound breaking, and to make it more easily handled, I have provided, with reference to Fig. 2, the shaft compound 1, contained with the bore of a cylindrical casing 2, the said casing being internally threaded to receive the externally threaded plunger shaft 3, having the projecting handle thereon, to effect rotation of the said shaft 3. It will be obvious that move- 105 110

ment of the shaft 3 of the handle 4 will advance the shaft compound 1 from the casing 2, a distance sufficient to suit the particular taste of the user.

5 The combination of a cleansing and bleaching compound shaped as a shaft with a casing, such as described, permits the same to be carried in the pocket much after the fashion of a pencil or pen. A modification 10 of the casing is shown in Fig. 3 wherein the shaft 1 is wrapped with continuous lengths of paper which may be easily and quickly torn and removed to lengthen the exposed position of the shaft 1 when the same becomes shortened through usage.

Having thus described this invention what I claim and desire to secure by Letters Patent is:—

1. A finger nail cleaner comprising a 20 cleansing compound shaped as a shaft in combination with means for containing said shaft.

2. A finger nail cleaner comprising a cleansing and bleaching compound shaped

as a shaft; an enclosing means for containing said shaft and means for discharging said shaft from said enclosing means.

3. A finger nail cleaner comprising a compound formed of an abrasive substance, a bleach and a binder and shaped as a shaft, 30 and an enclosing means for holding said shaft.

4. A finger nail cleaner comprising a compound formed of an abrasive substance, a bleach and a binder and shaped as a shaft 35 and means for discharging said shaft from said enclosing means.

5. A finger nail cleaner comprising a semi-solid cleansing compound shaped as a shaft and capable, of removing accumula- 40 tions from beneath finger nails in combination with means for containing said shaft.

In testimony whereof, I have hereunto set my hand at San Francisco, California, this 13th day of Sept., 1921.

CHARLES W. EADS.

In presence of—

LINCOLN JOHNSON.

DISCLAIMER

1,467,614.—*Charles W. Eads*, Oakland, Calif. FINGER-NAIL-CLEANING COMPOUND. Patent dated September 11, 1923. Disclaimer filed June 6, 1934, by the assignee, *Northam Warren Corporation*.

Hereby enters this disclaimer to claim 1 and to claim 5 of said Letters Patent No. 1,467,614, as follows:

1. It disclaims from the scope of claim No. 1, any shaft save one which has a substantially white color, and which includes a water-soluble binder.
2. It disclaims from the scope of claim 5 any shaft save one which has a substantially white color, and which includes a water-soluble binder.
